240,224

TELEPHONE INDEX SUPPORT ATTACHABLE TO A TELEPHONE BASE

Irwin H. Schneider, 12 Lee St., Stoneham, Mass. 02180,
and Terrance M. Carter, Woodbine Farm, Jaffrey Center,
N.H. 03454

Filed July 5, 1974, Ser. No. 485,837

Term of patent 14 years

Int. Cl. D14—03

U.S. Cl. D19—76

FIG. 1 is a top plan view of a telephone index support
attachable to a telephone base;

FIG. 2 is a front elevational view;

FIG. 3 is a left side elevational view; and

FIG. 4 is a bottom plan view thereof.

We claim:

The ornamental design for a telephone index support
attachable to a telephone base, as shown.
